(57) **CLAIM**

The ornamental design for a wall block, as shown and described.

DESCRIPTION

FIG. 1 is a perspective view of a wall block according to a first embodiment, as viewed from the front, top, and one side of the block.

FIG. 2 is a front elevation view of the wall block of FIG. 1.

FIG. 3 is a rear elevation view of the wall block of FIG. 1.

FIG. 4 is a left side elevation view of the wall block of FIG. 1.

FIG. 5 is a right side elevation view of the wall block of FIG. 1.

FIG. 6 is a top plan view of the wall block of FIG. 1; and, FIG. 7 is a bottom plan view of the wall block of FIG. 1. The broken lines in the drawings represent features of the wall block that form no part of the claimed design. The dash-dot-dash broken lines represent unclaimed boundaries and form no part of the claimed design.

1 Claim, 4 Drawing Sheets
